ELECTRON VELOCITY MODULATION TUBES

Arnold Hugh William Beck and Alan Butler Cutting, London, England, assignors to International Standard Electric Corporation, New York, N. Y.

Application July 23, 1953, Serial No. 369,805

Claims priority, application Great Britain August 1, 1952

8 Claims. (Cl. 315—5.47)

The present invention relates to electron velocity modulation tubes, and in particular to a novel construction of klystron amplifier tube.

In a two-resonator klystron amplifier tube an electron beam is projected across an input resonator so as to be velocity modulated by the electromagnetic field therein; the beam continues through a drift space in which the electrons become bunched and is then projected across an output resonator in which the bunched beam delivers up kinetic energy of the electrons in generating in the output resonator an electromagnetic field of greater energy than that supplied to the input resonator. For efficient amplification it is desirable that the equivalent shunt resistance of the output resonator be as high as possible. As with all tuned circuits, for a given bandwidth the shunt resistance is inversely proportional to the capacitance of the circuit, which, therefore, should be as low as possible. For efficient conversion of kinetic energy into electric energy of the field, it is necessary that the average transit time of an electron within the field be carefully chosen. In general a short transit time is desirable. This is achieved by allowing the electron beam to interact with the field at one or more short gaps whose boundaries of necessity contribute capacitance to the resonator. In many klystrons the resonators are of re-entrant form, the inter-action gaps being formed between the re-entrant portions. In the present invention the resonators are of generally cylindrical form and a sectionalised drift tube, positioned on the axis of the resonator is provided with gaps in which the beam may inter-act with the resonator field. The capacitances of these gaps are thus in series with one another and hence the total capacitance due to the electron system may be kept quite small, so that a high equivalent shunt resistance is obtained.

According to the present invention, there is provided a two-resonator klystron amplifier tube comprising: cylindrical input and output resonators positioned end to end along a common axis, a multi-sectioned drift tube extending the length of the said common axis, one of the drift tube sections communicating between the input and output resonators and the remainder of the sections intermediate the ends of the respective resonators being separated from one another by gaps; means for projecting a beam of electrons through the said drift tube, the said gaps between successive drift tube sections being of such length that the transit angles of an unmodulated electron of the said beam in each said gap is 2π radians; and respective coupling means for injecting electromagnetic wave energy into the input resonator and for extracting electromagnetic wave energy from the output resonator.

An embodiment of the invention will be described with reference to the accompanying drawings in which:

Fig. 1 shows, in part section, one view of a tube according to the present invention, the section being taken in the plane I—I of Fig. 2;

2

Fig. 2 is a further sectional view taken through the plane II—II of Fig. 1; and

Fig. 3 is a view, in part section, looking towards the tube from the left of Fig. 1.

5 The two resonators of the embodiment shown in the drawings are formed as a single copper block whose wall is indicated at 1. The block is sub-divided into two by a central transverse wall 2, which may be formed integrally with the cylindrical wall 1. End plates 3 and 4, closing the ends of the cylinder, are bonded to the wall 1, by for example, a gold diffusion process. A sectionalised drift tube 5 extends along the common axis of the two resonators, one of the sections 6 being secured in a central aperture of the dividing wall 2. The remaining 10 drift tube sections are separated by inter-action gaps of such length that the transit angle of an unmodulated beam electron in each gap is 2π radians. These intermediate drift tube sections are supported at their medial planes by respective radial rods 7 and 8 (Fig. 3) secured 15 in the wall 1. The rods securing adjacent drift tube sections are located on opposite sides of the axis of the resonators, so as to reduce as much as possible the capacitance between drift tube sections. In the embodiment illustrated four intermediate drift tube sections are 20 used in each resonator, so providing five inter-action gaps in each resonator. The rods may conveniently be made of copper plated tungsten so as to combine strength and rigidity. When the resonators oscillate in a pure T. M. mode the electric lines of force are everywhere parallel 25 to the resonator axis, so that the drift tube support rods do not disturb the field configuration.

A pair of cups of magnetic material, 9 and 10, are secured in central apertures of the respective end plates

3 and 4. Cup 9 houses an electron gun, cup 10 an electron collector electrode. These cups form pole pieces for a focusing magnet, not shown, which completes a focusing system of the kind described and claimed in an application of A. H. W. Beck, Serial No. 176,925, filed August 1, 1950.

Each cup has secured to it a sheet 40 metal member 11 suitable for sealing to glass. The cup 9 housing the electron gun is closed by a glass member 12 sealed to member 11, member 12 is carrying lead-out pins 13 for connection to an indirectly heated cathode 13 which is located in cup 9 by means of an insulating washer 15. The collector cup is closed by a glass collar 16 and an end plate 17 sealed to the glass, the end plate carrying a copper collector electrode 18. Both cups 9 and 10 are shown provided with portions 19 which form continuations of the drift tube 5.

50 Input and output connections to the respective resonators are provided by means of sections of rectangular wave guide 20 and 21 which are let into the cylindrical resonator wall 1 and are secured by means of an outer metal cylinder 23 surrounding the resonator block between the end plates 3 and 4. The wave guide sections 55 20 and 21 are terminated externally in a flange 24 by means of which the klystron amplifier may be coupled to further wave guide circuits. Secured to the flange 24 are two tuned diaphragms 25 and 26 provided with glass windows 27 separating the evacuated portion of the apparatus from the outside atmosphere.

Tuning of the resonators is accomplished by means of tuning strips 28 whose sides are mounted in trunnions 29 free to rotate in the wall 1 of the resonator block parallel to the cylindrical axis thereof. The ends of the strips 28 are provided with spring fingers 30 which contact the end surfaces of the respective resonators. The strips 28 are attached to respective piston rods 31 and 32 projecting through the resonator wall 1 and surrounding cylinder 23. This type of tuning mechanism forms the subject matter of U. S. Patent No. 2,737,631 granted March

6, 1956, on an application filed May 3, 1951. The piston rods 31 and 32 are secured to the respective base members 33 and 34 of a pair of metal bellows 35 and 36. The other ends of the bellows 35 and 36 are secured to the outer ends of members 23 as shown at 37, 38, 39 and 40. Ducts 41 in the wall 1 and cylinder 23 are provided for evacuating the interior of the bellows. The bellows and external tuning controls are supported between the top and bottom plates 3 and 4 of the resonators by means of the members 42 and 43. The base member 34 of bellows 36 is secured to a cross piece 44, free to slide in guides 45 and 46 in the respective members 42 and 43, by means of a rod 47 directly bolted to the cross member and fixed to the base member 34. The base member 33 of bellows 35 is provided with a rearwardly extending screwed rod 48 free to move axially in the cross member 44, the position of the base member 33 being adjustable by means of the knurled nut 49 which is located between channel walls of the cross member 44. The cross member 44 carries a screwed rod 50 free to slide in a bushing 51 which is secured to an end plate 52 which, in turn, joins the ends of members 42 and 43. The rod 50 is provided with a knurled nut 53 by means of which the cross member 44 may be moved along the guides 45 and 46 so providing axial movement of the base members 33 and 34 and hence simultaneous adjustment of the tuning strips 28. Adjustment of the nut 49 provides for differential tuning of the resonators.

While the principles of the invention have been described above in connection with specific embodiments, and particular modifications thereof, it is to be clearly understood that this description is made only by way of example and not as a limitation on the scope of the invention.

What we claim is:

1. A two-resonator klystron amplifier tube for operation over a given frequency band, comprising: cylindrical input and output resonators positioned end abutting end along a common axis; a multi-sectioned drift tube extending the length of the said common axis, one of the drift tube sections communicating between the input and output resonators and the remainder of the sections intermediate the ends of the respective resonators being separated from one another by gaps; means for projecting a beam of electrons through said drift tube, and respective coupling means for injecting electromagnetic wave energy into the input resonator and for extracting electromagnetic wave energy from the output resonator, the said gaps between successive drift tube sections being of such length that the transit angle of an unmodulated electron of the said beam in each said gap is 2π radians at the midband of the operating frequency of said tube.

2. An amplifier tube according to claim 1, in which the drift tube sections intermediate the ends of the respective resonators, are each supported by a radial rod secured to the wall of the said resonator, alternate rods lying on opposite sides of the axis.

3. An amplifier tube according to claim 1 said resonators comprising a cylindrical copper block having a central transverse wall centrally apertured to receive a drift tube section, and a pair of end plates mechanically bonded to the resonator block; and in which cups of ferromagnetic material, forming pole pieces for magnetic focusing of the electron beam, housing respectively an electron gun and a collector electrode, are secured in central apertures in the respective end plates.
- 10 4. An amplifier tube according to claim 3 in which the said cup housing the electron gun comprises a sleeve of an alloy sealing readily to glass secured to the said ferromagnetic material and to a glass cap, an indirectly heated cathode being mounted in the said cup, and leads to said cathodes being sealed through the said glass cap.
- 15 5. An amplifier tube according to claim 3 in which the said collector cup comprises a cylinder of ferromagnetic material closed at the end adjacent the resonator to which it is secured by a centrally apertured wall, an alloy sleeve sealing readily to glass secured to the said ferromagnetic member and to a glass collar, and a metal closure member forming a cap secured to the said glass collar and supporting an electron collector electrode centrally in the said cup.
- 20 6. An amplifier tube according to claim 3, in which each said resonator communicates through a port, respectively, to sections of rectangular wave guide secured in the said ports, each said wave guide section being hermetically sealed by means of a window of vitreous or ceramic material sealed to a tuned diaphragm mounted in the said wave guide section.
- 25 7. An amplifier tube according to claim 3 in which each said resonator comprises a tuning member extending from end to end of the resonator and short circuiting the end walls thereof, means being provided for adjusting the positions of the tuning members by respective piston rods passing through the resonator wall.
- 30 8. An amplifier tube according to claim 7 in which the said adjusting means comprises a pair of metal bellows, one secured adjustably and the other fixed to a cross member free to slide in guides in a pair of supporting members secured to the resonator block, and means for adjusting the base of one bellows with respect to the cross member and independent means for adjusting the position of the said cross member with respect to the support members.
